ELECTRIC SWITCH

Raymond N. Rowe, Plainville, Conn., assignor to
The Trumbull Electric Manufacturing Company, Plainville, Conn., a corporation of Connecticut

Application March 1, 1941, Serial No. 381,223

10 Claims. (Cl. 200—114)

My invention relates to what are commonly termed enclosed switches of the front operated type.

One object is to provide switch contacts and bridging members readily accessible and removable from the front.

Another object is to provide that all the normally replaceable current carrying parts may be easily accessible and replaceable from the front of the base.

Another object is to provide contacts and fuse terminals on different levels.

Another object is to provide a fused switch unit of compact arrangement wherein the switch contacts as well as the fuses are readily removable and replaceable.

Still another object is to provide a single insulating base with provision for mounting two independently functioning switches thereon.

Fig. 1 is a front view of an enclosed type of switch for manual as well as automatic operation involving my invention, the cover of the box being shown open. Only one switch and fuse unit is shown and the two companion units are merely suggested by dotted outlines.

Fig. 2 is a vertical section taken on the plane of the line 2—2 of Fig. 1, the cover being shown in the closed position.

Fig. 3 is a transverse sectional view of the construction shown in Fig. 1 with the cover closed.

Fig. 4 is a side view and partial section of a single switch and fuse unit of the duplex type shown in Figs. 1 to 3.

Fig. 5 is a transverse sectional view of the device of Fig. 4 taken on the plane of the line 5—5.

Fig. 6 is an exploded perspective view of the conducting parts at one end of a switch and fuse unit showing the circuit make and break contacts and one fuse terminal.

Fig. 7 is a similar view of a modified construction.

Fig. 8 is a side view and partial section of a switch and fuse unit having the conducting parts of Fig. 7 arranged for manual operation only.

Fig. 9 is a front view of the construction of Fig. 8.

Fig. 10 is a front view of a duplex type unit arranged for manual operation only.

Fig. 11 is a side view and partial section of the construction shown in Fig. 10.

Fig. 12 is a perspective view of the conducting member for supporting one end of a fuse and the associated circuit terminal as shown in Fig. 11.

Each switch and fuse unit has an insulating base 15 of general rectangular parallelepipedon shape to which are suitably attached the various circuit terminals, switch contacts and fuse terminals and which also supports the movable switch member or members depending upon whether it has a single or duplex switch. At one end is a circuit terminal 16 supported on a platform 17 and at the other end is the corresponding circuit terminal 18 on the platform 19 preferably on the same level as 17. A switch contact 20 is connected to terminal 16. The opposite switch contact 21 is mounted on the same level as 20. The movable switch member 22 is resiliently carried by a plunger 23 which is reciprocable through a passage in the base between the contacts 20 and 21. All of these parts excepting the plunger are removable from the front of the base. The switch member is mounted in a recess or chamber 24 formed between the walls 25 and 26 of the base.

The removable mounting of the contacts 22 may be as shown and claimed in Getchell's Patent 1,796,449.

25 The fuse clip or terminal 27 is connected to the metal strap 28 which is mounted on the platform 29 at the front of the base on a higher level than the switch contacts and at one side thereof. An arm 30 of the strap is bent at right angles and provided with a return bend 31 which is held beneath the switch contact 21. The fuse clip 32 is similarly connected to the strap 33 which has an arm 34 connected to a switch contact 35. This contact and its companion contact 36 are mounted on the platform 19 and contact 36 is connected to terminal 18. The movable switch member 37 is mounted similarly to switch member 22 but moves within the recess 38 similar to recess 24. A partition 39 separates the two recesses 24 and 38 and the conducting parts which are mounted therein.

When the switch members 22 and 37 are in closed circuit position, the current can flow from 16 to 20, 22, 21, 31, 30, 28, 27, the fuse (not shown), 32, 33, 34, 35, 37, 36 to 18.

Such units may be used singly, doubly or in triple as suggested in Fig. 1 where one unit has the base 15 and two other unit bases 15' and 15'' are suggested by dotted lines. These bases 50 are all mounted on a plate 40 and a single crank shaft 41 behind the base is connected to the respective plungers 23 etc.

To secure a snap action a second crank shaft 42 is provided and a toggle spring device 43 is 55 interposed between them. Shaft 42 has an arm

44 by which it can be actuated. In the form shown, the box 45 has a hinged cover 46.

The handle 47 is pivotally mounted on the cover and is provided on the inside with a lever 48 terminating in a curved arm 49 which has a slot in which an offset 50 of the crank arm 44 slides. This construction for manually actuating the upper switch units is more fully shown, described and claimed in my copending application Serial Number 349,907, filed August 2, 1940, now Patent No. 2,256,910, issued Sept. 23, 1941.

The lower switch units are actuated by a crank shaft 51 controlled by suitable electro magnetic mechanism not claimed herein but including local control switch mechanism 52 and 53 and an electro magnetic device 54. When the manual switch is closed the circuit can be opened and closed by means of the remotely controlled mechanism and of course is also protected by the fuses.

When the electro magnetic control is omitted, the same switch and fuse units may be employed but in this case the circuit from 34 to 48 is kept closed by a connector 60 as shown in Figs. 10, 11 and 12, the connector taking the place of the switch member 37 previously described.

It will be understood that the fuse clips 27 and 32 may be mounted at any desired spacing so as to permit the same construction to be used for various switch ratings.

The fuse clip straps 28 and 33 may themselves be provided with circuit terminals such as 65.

In Figs. 8 and 9 I have shown a modified form of insulating base and a somewhat different arrangement of electrical connections intended for a single switch control only. In this case the base 70 is of the same general shape as in the other figures and all the conducting parts are supported upon and removable from the front; the switch contacts being supported on surfaces nearer the rear than the fuse clips. The switch contacts 71 and 72 are secured to the base by screws 73 and 74 in a recess 75 formed between the walls 76 and 77. The movable switch member 78 is carried by a plunger 79 which is reciprocable through the base, and actuated by a crank 41 at the rear.

The fuse clips 80 and 81 are carried by straps 82 and 83 secured to a front platform 84 at a higher level than the switch contacts and at one side of them so that access can be freely had to both the fuse clips and the switch parts. The strap 82 has an arm 85 which extends back from the front of the base to the bottom of the recess 75 where it is connected to the switch contact 72. The circuit terminal 86 at the upper end of the base has a connecting bar 87 which extends along one side of the base and is connected to the switch contact 71. The fuse clip supporting strap 83 has a circuit terminal 88 at the lower end of the base.

When the switch member 78 is in closed position, current can flow as follows: from 86, 87, 71, 78, 72, 85, 82, 80, the fuse (not shown), 81, 83 to 88.

I claim:

1. A switch unit including a base portion having a flat front supporting surface and another flat supporting surface formed rearwardly and laterally of the front supporting surface, said rear supporting surface being formed with at least one opening extending to the rear of the base, a switch terminal at each end of the base, two contacts on the rear supporting surface on opposite sides of the opening, a switch carrier

extending through said opening, means for actuating the carrier from behind the base, a switch piece on said carrier, means removably securing the switch piece to the carrier, said means and said switch piece being accessible entirely from the front of the base, said contacts, carrier and switch piece being disposed rearwardly of the front supporting surface in all positions of the switch, a pair of spaced fuse terminal pieces mounted flat on the front supporting surface, a fuse holder on each fuse terminal piece, a strap connection between at least one of said terminal pieces and one of said contacts, means of connection between the other contact and one of said switch terminals and means of connection between the other fuse terminal piece and the other switch terminal.

2. A switch unit including a substantially rectangular insulating base having a forwardly protruding wall along one side edge with a front supporting surface and having another forwardly protruding wall along the central portion of the other side edge providing a space between said edge walls, said space having a rear supporting surface, a partition wall between said edge walls providing a chamber on each side thereof, the rear supporting surface in each chamber being formed with an opening extending to the rear of the base, two contacts on the rear supporting surface of each chamber on opposite sides of the opening therein, a switch carrier extending through each opening, means for actuating the carriers from behind the base, a switch piece on each carrier, means removably securing each switch piece to its carrier, a fuse terminal piece on said first named forwardly protruding wall above each chamber and spaced apart, a fuse holder on each fuse terminal piece, a strap connection between one of the contacts in each chamber with its respective fuse terminal piece thereabove and a wire connector connected to each of the other contacts in each chamber, said contacts, carriers and switch pieces being within said chambers rearwardly of the front supporting surface of said first named wall in all positions of the switch.

3. A switch unit including a substantially rectangular insulating base having a forwardly protruding wall along one side edge with a front supporting surface and having another forwardly protruding wall along the central portion of the other side edge providing a space between said walls, said space having a rear supporting surface, a partition wall between said edge walls providing a chamber on each side thereof, the rear supporting surface in each chamber being formed with an opening extending to the rear of the base, two contacts on the rear supporting surface of each chamber on opposite sides of the opening therein, a switch carrier extending through the opening in each chamber, means for actuating the carriers from behind the base, a switch piece on each carrier, means removably securing each switch piece to its respective carrier, said means and said switch pieces being accessible entirely from the front of the base, said contacts, carriers and switch pieces being within the chambers rearwardly of the front supporting surface of said first named side wall in all positions of the switch, a fuse terminal piece mounted flat on the front supporting surface of said first named side wall above each chamber, a fuse holder mounted on each fuse terminal piece, a strap connection between one of the contacts in each chamber with its respective fuse terminal piece

thereabove and a wire connector connected to each of the other contacts in each chamber.

4. A switch unit including a substantially rectangular insulating base having a forwardly protruding wall along one side edge with a front supporting surface and having another forwardly protruding wall along the central portion of the other side edge providing a space between said walls, said space having a rear supporting surface, a partition wall between said side walls providing a chamber on each side thereof, the rear supporting surface in each chamber being formed with an opening extending to the rear of the base, two contacts on the rear supporting surface of each chamber on opposite sides of the opening therein, a switch carrier extending through the opening in each chamber, means for actuating the carriers from behind the base, a switch piece on each carrier, means removably securing each switch piece to its respective carrier, said means and said switch pieces being accessible entirely from the front of the base, said contacts, carriers and switch pieces being within the chambers rearwardly of the front supporting surface of said first named side wall in all positions of the switch, a fuse terminal piece mounted flat on the front supporting surface of said first named side wall above each chamber, a fuse holder mounted on each fuse terminal piece, a strap connection between one of the contacts in each chamber with its respective fuse terminal piece thereabove, each strap connection extending substantially flatwise along and against a plurality of surfaces of the base and a wire connector connected to each of the other contacts in each chamber.

5. A switch assembly including an insulating base, a pair of contacts mounted on the base and accessible and removable from the front thereof, a wall on the base closely adjacent one side of the contacts and extending substantially further toward the front than the contacts, a conductor piece mounted on top of said wall, a second conductor piece mounted on top of said wall and spaced from the first piece, a fuse holder mounted on each conductor piece, means electrically connecting one of said pieces to one of said contacts, a movable switch carrying element extending from in back of the base to a position in front of the base and between the contacts, a switch member for bridging the contacts, mounted near the front end of the carrying element and accessible and removable from the front thereof, and means for operating said carrying element and said switch member, including mechanism located in back of said base, said contacts, carrying element and switch member being rearwardly of the level of said wall in all positions of said switch.

6. A switch unit including a substantially rectangular insulating base having a front main top surface and a recess having a rear surface below the main surface, said recess having a hole to the back of the base therein, two contacts mounted on the rear surface of the recess on opposite sides of the hole, a switch carrier extending through the hole, means for actuating the carrier from behind the base, a switch piece on said carrier, means removably securing the switch piece to the carrier, said means and said switch piece being accessible entirely from the front of the recess, said contacts, carrier and switch piece being within said recess below the main top surface of the base in all positions of the switch, a pair of spaced fuse terminal pieces

5 mounted flat on the main top surface of the base, a fuse holder mounted on each fuse terminal piece, a strap connection between at least one of said terminal pieces and one of said contacts and a wire connector fastened to the other contact of the pair of contacts.

7. A switch unit including a substantially rectangular insulating base having a main top surface and a recess having a surface below and rearwardly of the main surface, said recess having a hole to the back of the base therein, two contacts mounted on the surface of the recess on opposite sides of the hole, a switch carrier extending through the hole, means for actuating the carrier from behind the base, a switch piece on said carrier, means removably securing the switch piece to the carrier, said means and said switch piece being accessible entirely from the front of the recess, said contacts, carrier and switch piece being within said recess below the main surface of the base in all positions of the switch, a pair of fuse terminal pieces mounted flat on the main top surface of the base, a fuse holder mounted on each fuse terminal, a strap connection between at least one of said terminal pieces and one of said contacts, said connection extending substantially flatwise along and against a plurality of surfaces of the base and a wire connector fastened to the other of the pair of contacts.

8. An elongated one-piece insulating block having a circuit terminal at each end and having front and rear supporting levels, a switch having stationary contacts and a movable switch member located on the rear level and removable from the front of the base, fuse clips mounted on the front level of the base in a plane at one side of the switch contacts and removable from the front of the base, one of the switch contacts being connected to one circuit terminal, the other contact being connected to one of the fuse clips, the other fuse clip being connected to the other circuit terminal.

9. A switch assembly including an insulating base, a stationary contact on the base and accessible and removably from the front thereof, a wall on the base closely adjacent one side of the contact and extending substantially further toward the front than the contact, a safety fuse on top of said wall and connected to said contact, a movable switch carrying element extending from in back of the base to a position in front of the base, a switch member mounted near the front end of the carrying element and accessible and removable from the front thereof and means for operating said carrying element and switch member including mechanism located in back of said base, said contact, carrying element, and switch member being below the level of said wall in all positions of said switch.

10. A switch unit including an insulating base, having a front supporting surface and another supporting surface formed rearwardly and laterally of the front, said rear supporting surface being formed with an opening extending to the rear of the base, a wiring terminal adjacent each end of the base, a switching assembly including a switch contact on the rear supporting surface, a switch carrier extending through said opening, means for actuating the carrier from behind the base, a switch piece on the carrier for making and breaking a circuit with said contact upon movement of the carrier, and means removably securing the switch piece to the carrier, said means and said switch piece being accessible en-

tirely from the front of the base, all parts of said switching assembly being disposed rearwardly of the front supporting surface in all operating positions of the switch, a pair of spaced conducting pieces mounted flat on the front supporting surface, a fuse holder on each conducting piece, an electrical connection between

5 one of said conducting pieces and one side of the switching assembly, a connection between the other side of the switching assembly and one of the wiring terminals, and a connection between the other of said conducting pieces and the other wiring terminal.

RAYMOND N. ROWE.
